United States Patent Office

Des. 192,519
Patented Apr. 3, 1962

192,519

WATERING CAN OR SIMILAR ARTICLE

Nathan W. Roop, Columbus, Ohio, assignor to Columbus Plastic Products, Inc., Columbus, Ohio, a corporation of Ohio

Filed Sept. 8, 1961, Ser. No. 66,644

Term of patent 14 years

(Cl. D35—1)

FIG. 1

FIG. 2

FIG. 3

FIG. 4

FIG. 5

FIG. 1 is a side perspective view of a watering can showing my new design;

FIG. 2 is a top plan view on a slightly larger scale;

FIG. 3 is a side elevational view;

FIG. 4 is a front elevational view; and

FIG. 5 is a rear elevational view thereof.

I claim:

The ornamental design for a watering can or similar article, substantially as shown.
